his Atty's.

UNITED STATES PATENT OFFICE.

JOHN H. HOBBS, OF WHEELING, WEST VIRGINIA.

DESIGN FOR GLASS GOBLETS.

Specification forming part of Design No. 6,804, dated August 19, 1873; application filed March 8, 1873.

To all whom it may concern:

Be it known that I, JOHN H. HOBBS, of Wheeling, in the county of Ohio and State of West Virginia, have invented a new and useful Design for Pressed Goblets and Goblet-Molds; and I do hereby declare the following to be a full, clear, and exact description thereof, reference being had to the accompanying drawing making a part of this specification, in which—

Figure 1 is a vertical section of a glass-mold, showing a plunger and cavities suitable for forming the goblet; and Fig. 2 shows, in elevation, a pressed-glass goblet, illustrative of my improved design.

My improved design consists in the peculiar taper form given to the pressed-goblet bowl, as shown and described.

The foot, stem, and base of the bowl are of any desired form, made in suitable cavities *c*

c' c''. The bowl *n* is made in the cavity *e*, so as to have a taper form, substantially as shown, with the up-and-down lines of its sides approaching nearly or quite to straight lines through the greater part of their length, the upper part being curved slightly inward to give a mouth with vertical sides, and the lower ends of said lines being tangential to the curve of the base of the bowl.

What I claim as my improved design, and desire to secure by Letters Patent, is—

The design for pressed goblet-bowls, shown and described.

In testimony whereof I, the said JOHN H. HOBBS, have hereunto set my hand.

JOHN H. HOBBS.
